UNITED STATES PATENT OFFICE.

WILHELM SCHMIDT, OF CASSEL-WILHELMSHÖHE, GERMANY, ASSIGNOR TO SCHMIDT'SCHE HEISSDAMPF-GESELLSCHAFT M. B. H., OF CASSEL, GERMANY, A CORPORATION OF GERMANY.

ENGINE.

1,092,543.

Specification of Letters Patent.

Patented Apr. 7, 1914.

Application filed December 16, 1911. Serial No. 666,276.

To all whom it may concern:

Be it known that I, WILHELM SCHMIDT, a subject of the King of Prussia, Emperor of Germany, and resident of Cassel-Wilhelmshöhe, Germany, have invented certain new and useful Improvements in Engines, of which the following is a specification.

My invention relates to engines driven by steam or other impelling fluid, and especially 10 to such engines when required for high duty.

More particularly, my invention relates to engines as those specified of the reciprocating type when required to operate with a high rate of revolution of the driving shaft 15 *i. e.*, a high piston velocity. By high piston velocity I mean a velocity as great as ten meters per second.

My invention also relates to a compound engine of the character specified comprising 20 a high pressure part of the character just specified and a low pressure part comprising a turbine, the two parts being arranged to directly operate one and the same shaft.

The object of my invention is to produce 25 an engine of the character set forth whereby certain gains in efficiency, durability, economy of manufacture, simplicity of operation, space required for installation and other advantages to be later set forth shall 30 be realized.

The character of my invention will be better understood with reference to the drawing accompanying which is hereby made a part of the specification and in which—

35 Figure 1 represents a plan view partly in section of a preferred form of compound steam engine embodying my invention; Fig. 2 represents a vertical transverse section along the line 2—2 of Fig. 1; Fig. 3 represents a detail considerably enlarged of the 40 governing valve at the end of each steam cylinder; and Fig. 4 represents diagrammatically a modification of the reciprocating engine part of my invention.

45 Referring to the drawings, a main frame *a* has mounted upon it at one end a reciprocating engine and at the other end a turbine of any convenient construction. In suitably-arranged bearings *b* is mounted a rotating 50 shaft *c* common to both the engine and the turbine *d*.

The reciprocating engine comprises eight independent and identical simple reciprocating engines lying in the same plane, and in

the plane of the shaft, four upon one side of the shaft and four upon the other side, each set of cylinders being uniformly spaced apart and in alignment respectively with the cylinders at the other side. The shaft *c* is provided with four cranks corresponding with the four pair of oppositely-arranged cylinders, these cranks all being arranged in the plane of the shaft with the two center cranks on one side of the shaft and the two extreme cranks at the other side of the shaft. The connecting rods *g* belonging to the pistons *f* of opposite cylinders are therefore applied to the same crank. The ends of these piston rods do not completely encircle the crank but are formed as circular segments of substantially less than 180° and abutted against said cranks. Since the steam pressure is only active on the outward stroke of the piston and a very high compression is preferably chosen, this practice suffices to keep the ends of the connecting rod in constant contact with the cranks since the engine operates at such high speed that the connecting rods have no opportunity to fall away from the cranks. To keep the connecting rods in place, however, when the engine is dead, or running with steam cut off, rings *h* which encircle both the connecting rod segments and the crank are provided.

Owing to the inertia of reciprocating parts a reciprocating engine is, inherently, as ordinarily constructed, a slow speed engine. My improved reciprocating engine as here disclosed however permits the use of such relatively small cylinders, pistons, connecting rods and other parts that an engine of large power may be constructed to run at high speed. In the attainment of this high speed the fact that, as is evident, the moving parts are almost perfectly balanced against one another while the pressures are also balanced against one another, is very important. The crank shaft is also, it will be noted, balanced end for end.

To reduce vibration to a minimum I prefer to use on the reciprocating part of my improved engine an automatic governor. The one shown in the drawings is one of the type shown by my German Patent No. 76,651 of Sept. 4, 1894 and the operation of said valve is explained in said patent.

In the modification shown in Fig. 4 the reciprocating engine comprises two sets of

eight engines arranged in two planes at right angles to one another each set being arranged as shown in Figs. 1 to 3 and above described and a shaft as shown in such figures being common to both sets.

It is to be understood that I do not restrict my invention to the above described reciprocating engine since in many cases the balancing of pressures may be dispensed with. It is only essential that a large powered reciprocating engine should be made up of a plurality of small independent and identical engines arranged in the manner shown and with their reciprocating and rotating masses balanced.

Having described my invention, I claim:

1. A steam engine comprising, in combination, a shaft, and a plurality of identical single acting engines having their cylinders and said shaft in a common plane and disposed in groups of eight with four on one side and four on the other side of the shaft, the shaft being provided with cranks also in one plane the cranks corresponding to the four outside engines being opposite to those corresponding to the four central engines, and both cylinders and cranks being symmetrical as to a plane perpendicular to the shaft and midway as to the central engines.
2. A steam engine comprising, in combination, a shaft and a plurality of identical single acting engines arranged in two groups having their cylinders at right angles to one another each group having its cylinders in a plane common to said shaft and disposed in sub-groups of eight with four on one side and four on the other side of the shaft, the shaft being provided with cranks corresponding to the two engine groups, the cranks all being in a single plane, the cranks corresponding to the four outside engines being opposite to those corresponding to the four central engines, and both cylinders and cranks being symmetrical as to a plane per-

pendicular to the shaft and midway as to the central engines.

3. A steam engine comprising, in combination, a shaft, and a plurality of identical single acting engines having their cylinders and said shaft in a common plane and disposed in groups of eight with four on one side and four on the other side of the shaft, the shaft being provided with cranks also in one plane the cranks corresponding to the four outside engines being opposite to those corresponding to the four central engines, the piston rods of the several engines, furthermore, being abutted against but not attached to the cranks, and both cylinders and cranks being symmetrical as to a plane perpendicular to the shaft and midway as to the central engines.

4. A compound steam engine comprising a turbine for low pressure element and a reciprocating engine for a high pressure element the two elements being provided with a common shaft and the high pressure element comprising, further, a plurality of identical single acting engines having their cylinders and said shaft in a common plane and disposed in groups of eight with four on one side and four on the other side of the shaft, the shaft being provided with cranks also in one plane the cranks corresponding to the four outside engines being opposite to those corresponding to the four central engines, and both cylinders and cranks being symmetrical as to a plane perpendicular to the shaft and midway as to the central engines.

In testimony whereof I have hereunto set my hand in the presence of two subscribing witnesses.

WILHELM SCHMIDT.
